VEHICLE ACTUATED PROGRESSIVE TRAFFIC SIGNAL

Charles W. Neill, Syracuse, N. Y., assignor to Creuse-Hinds Company, Syracuse, N. Y., a corporation of New York

Application September 15, 1930, Serial No. 481,878

4 Claims. (Cl. 177—337)

This invention relates to traffic signals and particularly to traffic signal systems in which a plurality of the signal devices are vehicle actuated.

5 It is well recognized that in traffic signal systems in which the right of way indications are shifted by arbitrary timing devices, much time is lost as the result of signal changes in favor of streets on which no traffic is moving at the time.

10 The vehicle actuated traffic signal is a development which saves much time and greatly increases the efficiency of the isolated intersection which is controlled by traffic signals. When vehicle actuated signals are used at successive 15 intersections along a highway, much of their efficiency is lost and the operation is no more efficient than in the case of traffic officers. It is well known that in driving along a street where the traffic at each intersection is directed by an officer, it is often necessary for a vehicle to stop 20 at most, and sometimes at all, intersections.

The principal object of this invention is to provide a traffic signal system in which traffic may move along a highway and obtain a go signal at each intersection, and to provide vehicle actuated means for controlling the operations of the signals so as to obtain the increased efficiency produced by having the signals vehicle operated. A further object of the invention is to provide a 25 plurality of signal devices for directing traffic at the intersections along a highway and to provide operating mechanism for the signal devices which will normally display a go signal indication to traffic on the cross street but which will be operated by vehicle actuated means, to give go signal indications to a vehicle, or a platoon of vehicles, moving progressively along the highway.

30 Other objects and advantages of the invention will appear and will be pointed out as the description proceeds.

The invention consists in the novel features and in the combinations and constructions herein-after set forth and claimed.

45 In describing this invention reference is had to the accompanying drawing in which like characters designate corresponding parts in all the views.

50 Figure 1 is a diagrammatic plan view of a highway, intersected by a plurality of cross streets, showing the timing devices for rendering the vehicle actuated control means operative.

55 Figure 2 is a wiring diagram of the mechanism for operating the signal devices at the respective intersections shown in Figure 1.

Progressive control of signals

Figure 1 shows a highway intersected by a plurality of cross streets and signal devices 11, 12, 13 and 14 are shown located at the respective intersections. These signal devices are of conventional construction and are therefore shown diagrammatically in Figure 1. The right of way indications displayed by the signal devices will normally indicate go to traffic on the cross streets and stop to traffic on the highway. The signal devices are shown in this position in Figure 1 in which G designates a go signal indication and S designates a stop signal indication. As long as there is no traffic moving on the highway, the traffic on the intersecting streets may cross without interference from the signal devices. Vehicle actuated means are provided for shifting the signals to indicate go to traffic on the highway and stop to traffic on the cross streets. The vehicle actuated means include shifting mechanism, which will be described in detail hereinafter, and vehicle actuated detector means for controlling the operation of the shifting mechanism. This detector mechanism may be of any suitable type such as the treadle devices shown in Patent No. 1,194,668 to Schatzle et al., August 15, 1916, or Patent No. 1,665,560 to Nelson, April 10, 1928, or may be of the magnetic type. Two detectors 20 and 21 are provided to control the shifting of the signal device 11. The detector 20 is located on the right side of the street for vehicles moving along the highway toward the right in Figure 1. The detector 21 is located on the right side of the highway for vehicles moving along the highway toward the left in Figure 1. The connection between these detectors, 20, 21 and the means for shifting the signal indications will be described in connection with Figure 2 of the drawing. Two detectors 22, 23 are provided for operating the mechanism for shifting the signal indications of the signal device 12. Corresponding detectors 24 and 25 are provided for controlling the operation of signal device 13. A detector 26 operates to control the signal device 14 and a second detector will be located on the other side of the signal device 14, outside the field of the drawing.

The detailed construction of the detectors is unimportant but they are of the type which when operated closes an electric circuit. It is necessary, therefore, to supply electric power to these detectors and if the supply of electric power is cut off, the detectors become inoperative to control the shifting of the signal devices. The signal

system shown in Figure 1 is designed to be operated progressively by dividing the traffic on the highway into platoons and giving a go signal at the respective intersections progressively so that a platoon after passing the first intersection may move continuously at a predetermined rate of speed and always receive a go signal indication at each succeeding intersection. This manner of directing traffic to obtain continuous movement is well understood by those skilled in the art. If the signal device 11 displays a stop signal indication to traffic on the highway for a period of time, a platoon will form on the highway. If the signal device 11 is then shifted to give a go signal indication, a platoon may move to the right toward the signal device 12. If the first car of this platoon crosses the detector 22 and causes the signal device 12 to shift to give a go signal indication to the highway traffic, the platoon may move along the intersection controlled by the signal device 12 without stopping. If the detector 24, in response to actuation by the first vehicle of the platoon, shifts the signal device 13 to indicate go to highway traffic, the platoon may continue to move without stopping. In such platoon movement of traffic however, it is necessary that some space be maintained between platoons to permit traffic on the cross streets to pass across the intersections. It is necessary, therefore, that the detectors 20, 21, 22, 23, 24, 25 and 26 be rendered inoperative to cause the signal indications to shift if a vehicle approaches on the highway between the periods during which a platoon is due to cross the intersection. The detectors are rendered inoperative to control the shifting of the signal indications by periodically cutting off the supply of electric power to the detectors.

Electric power is furnished to the detector 20 through a conductor 30 which connects with a brush 31. The brush 31 runs on a commutator 33 which is driven by a continuously rotating synchronous motor 35. The commutator 33 is provided with a hot segment 37 and an insulating segment 38. When the brush 31 is in contact with the hot segment 37 the conductor 30 supplies electric power to the detector 20 and if a vehicle actuates the detector 20 the signal device 11 will be shifted to give a go signal indication to the highway traffic. When the brush 31 is in contact with the insulating segment 38, the supply of power to the detector 20 is cut off and the detector 20 is inoperative to control the shifting of the signal device 11. Thus vehicles approaching the detector 20 and signal device 11 during the period that the brush 31 is in contact with the insulating segment 38 will have to wait until the hot segment 37 moves into contact with the brush 31. It is during this time that an accumulation of traffic forms on the highway and when the hot segment 37 comes in contact with the brush 31 and the detector 20 operates the shifting mechanism to cause the signal device 11 to indicate go to the highway, a platoon of traffic whose length is determined to a large extent by the time of display of the said go signal, will cross the intersection controlled by the signal device 11 and begin its progressive movement along the highway.

The supply of power to the detector 22 is controlled by a commutator 43 which is of identical construction with the commutator 33 and is provided with a hot segment 37 and an insulating segment 38. The commutator 43 is operated by a continuously rotating synchronous motor 45

and the synchronous motors 35 and 45 are run from the same power line so that the commutators 33 and 43 rotate at exactly the same rate of speed. If the commutators 33 and 43 rotate in a counter-clockwise direction, the hot segment 37 of the commutator 43 will be spaced in a clockwise direction from the hot segment 37 of the commutator 33. By having the hot segment 37 of the commutators 33 and 43 so set with respect to one another, the hot segment 37 of the commutator 43 will come in contact with the brush 31, to furnish power to the detector 22, some time after the hot segment 37 of the commutator 33 has come in contact with the brush 31 to supply power to the detector 20. Thus the detector 22 becomes operative to control shifting of the signal device 12 some time after the detector 20 becomes operative to control shifting of the signal device 11. The length of this time may be adjusted by changing the setting of the hot contact segment 37 of the commutators 33 and 43 with respect to one another. Obviously, the commutators will be set to obtain a greater lapse of time if the distance between the signal devices 11 and 12 is longer than if this distance is comparatively short. If the speed of progression of the traffic platoons is to be slow, the commutators 33 and 43 will be set so as to obtain considerable lag after power is furnished to the detector 20 before it is furnished to the detector 22. If the traffic moves at a high speed of progression, the time lag between the power supply to the detectors 20 and 22 may be very short.

A commutator 48 driven by a synchronous motor 49 furnishes power to the detector 24 in exactly the same manner as described in connection with detectors 20 and 22. The commutator 48 will be so set with respect to the commutator 43 that the supply of power to detector 24 will occur some time after the supply of power to the detector 22 and the length of this time may be adjusted to suit the distance between intersections or the speed of progression. The detector 26 receives its power supply from a commutator 53 which is continuously rotated by a synchronous motor 55. From the above description it will be apparent that the commutators 33, 43, 48 and 53 may be set in any desired relation to one another so as to obtain uniform speed of progression regardless of the distance between intersections, to obtain progression at a non-uniform rate, or to obtain a supply of power to their respective detectors in any desired sequence.

If the highway shown in Figure 1 were a one-way street, the detectors 20, 22, 24 and 26 would be sufficient to shift the signal devices. If the highway is to operate with two-way traffic, the detectors 21, 23 and 25 become necessary. These detectors 21, 23 and 25 are supplied with electric power by commutators 57, 58 and 59, respectively, which are operated by synchronous motors 60, 61 and 62, respectively. The commutator 53 furnishes power to a detector on the other side of the signal device 14 outside of the field of the drawing. The operation of the commutators 57, 58, 59 and 63 is identical with the operation of the commutators 33, 43, 48 and 53 except that the commutators 57, 58, 59 and 63 will be set so as to obtain a time lag for traffic moving in the opposite direction. That is, the commutator 58 will be set with respect to the commutator 59 so that the supply of power to the detector 25 will occur before the supply of power to the detector 23. This difference in setting is obviously necessary due to the fact that the detectors 21, 23

and 25 control the signal devices for platoons progressing from right to left along the highway in Figure 1. The synchronous motors 60, 61 and 62 are connected with a different power line than 5 the synchronous motors 35, 45, 49 and 55. It is immaterial, however, whether two power lines are used or a single power line used for all 10 motors tho it is necessary that all the motors on one side of the street operate in synchronism 15 and that the motors on the other side of the street operate in synchronism while the separate systems of the motors on opposite sides of the street may or may not be synchronized. It is not necessary that an individual motor be supplied to each commutator.

Signal shifting mechanism

The signal shifting mechanism is shown in Figure 2 and is controlled by a detector such as 20 the detector 20 which contains an armature 70 to which power is supplied through the conductor 30. Actuation of the detector 20 by a vehicle will cause the armature 70 to drop into contact with the contact point 72.

25 The shifting mechanism is operated by a motor 74 which rotates in a clockwise direction but is normally stationary. A conductor segment 75 is rotated by the motor 74. When the shifting mechanism is in normal position the conductor 30 segment will occupy the position shown in Figure 2 with a brush 78 out of contact with the conductor segment and a brush 80 in contact with one end of the conductor segment as shown. The conductor segment 75 is hot at all times 35 and when the shifting mechanism is in its normal position, power from the conductor segment 75 will flow through the brush 80, a conductor 81, armature 82, contact point 83, and conductor 85 to light the cross street go signal. A conductor 86 connects the conductor 85 with the highway stop signal.

When a vehicle actuates the detector 20 to drop the armature 70 into contact with the contact point 72, power is supplied from the conductor 30, through the armature 70, contact point 72, and conductor 89 to a relay 90. The other side of the relay 90 is connected by a conductor 91 with a relay 92. The other side of the relay 92 is connected by a conductor 95 with a driving coil 96 of the motor 74. Thus actuation of the detector 20 transmits power to the driving coil 96 to operate the motor 74 which rotates the conductor segment 75.

The relay 90 operates an armature 100 which 55 is normally held away from the relay by a spring 102. The upper end 104 of the armature 100 is insulated from the other part of the armature and acts as a switch to make contact between the contact points 105 and 106, the purpose of 60 which is to operate the caution signal as will be further explained hereinafter. The lower end of the armature 100 is connected by a conductor 108 to the conductor 81. A contact point 110 is provided to make the relay 90 stick.

65 When current is supplied to the relay 90, as above described, the armature 100 will be drawn into contact with the contact point 110. Power will be supplied to the relay 92 at the same time and the armature 82 will be drawn 70 into contact with a contact point 112. The movement of the armature 100 into contact with the contact point 110 will establish a circuit from the conductor segment 75 through the brush 80, conductors 81 and 108, armature 100, contact point 110, relay 90, conductor 91, relay

92, and conductor 95, to the driving coil 96 of the motor. Since the relay 90 is a stick relay, this circuit will continue as long as the brush 80 is in contact with the conductor segment 75.

5 The armature 82 is normally held in contact with the contact point 83 by a spring 114. When the armature 82 is shifted out of contact with the contact point 83 and into contact with the contact point 112, the circuit to the cross street go signal and highway stop signal is broken and a new circuit is set up to the caution signals. This circuit to the caution signals is furnished with power from the conductor segment 75, 10 through the brush 80, conductor 81, armature 82, contact point 112, conductor 115, armature 117, contact point 118, and conductor 120 to the 15 caution signals.

The caution signals will remain displayed until the motor 74 has rotated the conductor segment 75 to bring the conductor segment 75 into contact with the brush 78. When the conductor segment 75 makes contact with the brush 78 power will be supplied through a conductor 122, relay 124 and a conductor 125 which connects with the conductor 95 to furnish a parallel circuit for the supply of power to the driving coil 96 of the motor. When current flows through the relay 124 the armature 117 will be moved, against the tension of a spring 127, to break the circuit through the contact point 118 and establish a new circuit from the armature 117 through a contact point 130 and a conductor 132 which connects with the cross street stop signal. A conductor 133 connects the conductor 132 with the highway go signal.

35 The highway go signal and cross street stop signal will remain displayed as long as the conductor segment 75 is in contact with both of the brushes 78 and 80. When the motor 74 has rotated the conductor segment 75 until the conductor segment 75 passes out from under the brush 80, the circuit through the brush 80, conductors 81 and 108, armature 100 and contact point 110 to the relays 90 and 92 will be broken. The springs 102 and 114 will move the armatures 100 and 82, respectively, out of contact with the contact points 110 and 112, respectively, and into contact with the contact points 105, 106 and 82. Although the circuit through the relays 90 and 92 to the driving coil 96 is thus broken, the motor 74 will continue to run since power is supplied to the driving coil 96 from the brush 78 and through the conductor 122, relay 124 and conductor 125. The breaking of the circuit from the armature 82 through the contact point 112 will cut off the supply of power to the armature 117 and the highway go signal and cross street stop signal will no longer be displayed.

40 The contact point 105 is connected by a conductor 135 with the brush 78 and when the spring 102 restores the armature 100 to normal position, power from the conductor segment 75 will be supplied through the brush 78, conductor 135, contact point 105, end portion 104 of the commutator 100, contact point 106, and conductor 136 to the caution signals.

45 When the motor 74 has rotated the conductor segment 75 through a complete revolution so that it returns to its normal position, as shown in Figure 2, the contact between the conductor segment 75 and the brush 78 will be broken and the supply of power through the conductor 135 to the caution signals will be cut off. Also the supply of power to the relay 124 and motor coil 50 55 60 65 70 75 80 85 90 95 100 105 110 115 120 125 130 135 140 145 150 155 160 165 170 175 180 185 190 195 200 205 210 215 220 225 230 235 9190 9195 9200 9205 9210 9215 9220 9225 9230 9235 9240 9245 9250 9255 9260 9265 9270 9275 9280 9285 9290 9295 9300 9305 9310 9315 9320 9325 9330 9335 9340 9

restore the armature 117 to its normal position in contact with the contact point 118, and the motor 74 will stop since no circuits are closed which will supply power to the driving coil 96.

5 The conductor segment 75 will make contact with the brush 80 just before the shifting mechanism reaches normal position and the supply of power from the brush 80 to the cross street go signal and highway stop signal will be restored.

10

Time extension

Means are provided to extend the time of the highway go signal to permit long platoons to cross before the signals return to normal position. The time extension means include a conductor 140 which connects the contact point 72 with a bucking coil 142 which is associated with the motor 74. As long as the armature 70 is held in contact with the contact point 72 power will be supplied from the armature 70, through the contact point 72, and conductor 140 to the bucking coil 142 which is arranged to counteract to a large extent, the effect of the driving coil 96 and thus causing the motor 74 to operate at a greatly reduced rate of speed. The greater the number of vehicles which actuate the detector 70 during a highway go period, the greater will be the bucking effect of the coil 142 and the time required for the conductor 75 to make a complete rotation will thus be increased to accommodate the length of the platoon. The bucking coil 142 may be of sufficient strength to entirely stop the motor 74 and preferably the amount of current flowing through the bucking coil 142, and the consequent retarding effect of this coil, is adjusted by means of an adjustment resistance 144 which is inserted between the conductor 140 and the bucking coil 142.

From the foregoing description it will be apparent that I have devised a particularly efficient signal system for directing street traffic. This system is illustrated in its preferred embodiment but changes and modifications may be made without departing from the spirit of the invention as set forth in the appended claims.

What I claim is:

1. In a street traffic signal system for a highway intersected by a plurality of cross streets, signal devices at the respective intersections and normally indicating right of way to traffic on the cross streets; mechanism for shifting the right of way indication to the highway, including vehicle actuated means in the highway associated with each of the shifting devices, for con-

trolling the shifting of the right of way indication to the highway; a timer associated with each vehicle actuated means for periodically rendering said vehicle actuated means effective, each of said timers being operable in a predetermined timed relationship with the timers at adjacent intersections, whereby the vehicle actuated means are rendered effective upon actuation by vehicular traffic to shift the signal indications progressively down the highway.

5

10

2. In a street traffic signaling system for a highway intersected by a plurality of cross streets, signal devices at the respective intersections normally indicating right of way to the cross streets and stop to the highway, means associated with the signal device at each intersection and operable, upon actuation by a vehicle on the highway, to shift the right of way indication to the highway and stop to the cross street, and means for periodically rendering said actuation of each shifting means effective only in a related predetermined sequence.

15

20

3. In a street traffic signaling system for a highway intersected by a plurality of cross streets, signal devices at the respective intersections normally indicating right of way to the cross streets and stop to the highway, a traffic actuatable controller associated with each signaling device and operable, upon actuation by a vehicle on the highway, to shift the right of way indication to the highway, and stop indication to the cross street, and means for rendering the actuation of each controller effective to cause said shift of right of way indication at each succeeding intersection only in a related predetermined sequence.

25

30

35

4. In a street traffic signaling system for a highway intersected by a plurality of cross streets, signal devices at the respective intersections normally indicating right of way to the cross streets and stop to the highway, a traffic actuatable controller associated with each signaling device and operable, upon actuating by a vehicle on the highway, to shift the right of way indication to the highway, and stop indication to the cross street, and to maintain said signal devices in such shifted condition for a predetermined length of time and subsequently return said signal devices to normal indication, and means for rendering the actuation of each controller effective to cause said shift of right of way indication at each succeeding intersection only in a related predetermined sequence.
